FURNITURE PULL OR THE LIKE

Nolan Kent Rhoades, Beloit, Wis., assignor to National
Lock Co., Rockford, Ill., a corporation of Delaware

Filed Feb. 16, 1962, Ser. No. 68,865

Term of patent 14 years

(Cl. D10—8)

FIG. 1 is a front elevational view of a furniture pull or the like embodying my new design;

FIG. 2 is a top plan view thereof;

FIG. 3 is a rear elevational view thereof;

FIG. 4 is an end elevational view thereof; and

FIG. 5 is a cross-sectional view on the line 5—5 of FIG. 1.

I claim:

The ornamental design for a furniture pull or the like, substantially as shown.
